(57) **CLAIM**

The ornamental design for a twirling prop, as shown and described:

DESCRIPTION

FIG. 1 is a left side elevational view of a twirling prop showing our new design, the right side being a mirror image;

FIG. 2 is a front elevational view thereof;

FIG. 3 is a rear elevational view thereof;

FIG. 4 is an enlarged scale top plan view thereof; and,

FIG. 5 is an enlarged scale bottom plan view thereof.
